UNITED STATES PATENT OFFICE.

MENDEL OSNOS, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

TELEPHONY OR KEYING ARRANGEMENT.

Application filed October 22, 1925, Serial No. 64,246, and in Germany November 15, 1924.

In U. S. patent application Serial No. 63,618, filed October 20, 1925, and United States Patent No. 1,603,491, an arrangement adapted to control or modulate high frequency currents has been disclosed. The controlling device consisted of an iron-coated or iron-covered or iron-wrapped current conductor which, apart from the high frequency currents, is traversed also by the controlling currents.

If the value of the controlling currents flowing in a given axis are to be reduced with reference to the high frequency currents flowing in another axis, the controlling device, as indicated in the above application, can be so formed that its conductors are divided into several groups which are disposed in series for the controlling currents, and in parallel for the high frequency currents flowing in the other axial direction.

In this modulator device the difficulty is frequently encountered that the controlling currents, in order to be able to produce an effective influence upon the device, must have approximately the same order of magnitude as the high frequency currents to be controlled, while it is desirable, on the other hand, especially in telephony work, to operate with as small controlling currents as possible.

This difficulty is obviated according to the present application in that the device which accomplishes the controlling action (regardless of whether it serves as a pure telephony or keying choker, or at the same time as a frequency-changer) is coupled by means of current transformers with the other circuits to be regulated. The ratio of transformation of the current transformers must be so chosen that in the circuit or circuits of the controlling device the currents are reduced to the lowest value that may be convenient. For instance, the ratio of transformation may be made 1:100. The current transformer, in well-known manner, may be of the single-coil auto-transformer type, or of the two-coil or coupler coil kind, or else be built similarly to ammeter current (instrument) transformers.

My invention in its preferred form is illustrated by the accompanying drawing wherein Figs. 1 and 1^a illustrate two fundamental ideas of frequency changer or modulator systems; Fig. 2 shows a means for utilizing

my invention as both a frequency changer and modulator; Figs. 3 and 3^a show modified forms of Fig. 2 wherein the output currents are fed to a load circuit from different terminals; Fig. 4 shows a preferred modification applying my invention to a modulator only and supplying a separate frequency changer; Fig. 5 illustrates a further modification of Fig. 4 with a direct coupling of the frequency changer to the antenna load circuit; and Fig. 6 shows a preferred embodiment wherein the arrangement may be used as both a frequency changer and modulator.

In Figs. 1 and 1^a a number of construction forms of the said device are illustrated. Referring to the figures, α_1 and α_2 are the parts made up of the said iron-coated conductor. The controlling currents are fed in the direction $l_1 l_2$. If the device is only used as a modulator choke coil, it is possible to control the high frequency currents flowing in the direction $k_1 k_2$. If the device is used at the same time as a frequency changer the primary current flow in the direction $k_1 k_2$, while the currents of secondary frequency can be taken off at the terminals $k_1 k_2$ for odd harmonics and at the terminals $l_1 l_2$ for even multiples.

A number of forms of construction of the idea underlying the invention are shown by way of example in the accompanying drawing. In the case of an arrangement as depicted in Fig. 2 the apparatus α effecting the control is simultaneously used as a frequency changer; it is joined with the circuit l by a current transformer t_1 , and with the aerial circuit by a current transformer t_2 which is built at the same time as a variable coupler. The high frequency currents flow through device α in the direction $k_1 k_2$ by way of condensers CC ; the modulation currents furnished from a control current source m which may be, for example, a microphone, a cathode, tube, or the like, flow in the direction $l_1 l_2$.

The arrangements shown in Figs. 3 and 3^a differ from the one before shown only in so far as in this case the secondary currents (especially those of an even multiple) are not delivered at terminals $k_1 k_2$, but at terminals $l_1 l_2$. This arrangement is particularly advantageous since the controlling device is especially sensitive to variations of the

modulating currents, so that not only the modulating current, but also the modulator energy can be chosen very small.

In the form of construction according to Fig. 4, the controlling apparatus *a* serves exclusively as a modulator choker (telephony choker), the frequency raising being, if desired, accomplished by means of a special frequency changer *f*, arranged in the circuit I.

As shown in Fig. 5, frequency changer *f* can be coupled with the aerial circuit also directly (by galvanic means or through a coupler coil *k*), the modulator coil *a* being coupled only with the antenna circuit, also in this case through a current transformer *t₂*.

In a great number of cases it may be found advantageous to make the device effecting the control bifilar in nature not only with reference to axis *l₁ l₂*, but also to axis *k₁, k₂*. However, it is also possible to save one of the current transformer windings in the circuit of the controller apparatus, provided the conductor constituting the said device is conveniently shaped. Starting, for instance, from the arrangement Figs. 1 or 1^a, where the two conductor parts *a₁ a₂* are bifilar for the controlling currents supplied at terminals *l₁ l₂*, the conductors *a₁, a₂* shown stretched or straight in the direction *k₁, k₂*, without changing their relative position, can be bent circular or angularly in several turns, with the ends *k₁, k₂*, being short circuited. The coil formed in this manner, in an arrangement as shown in Fig. 5, can at the same time be used as the primary coil of the current transformer *t₂*. It goes without saying that also the current transformer can be constructed in any desired manner, similarly to the current transformers used in conjunction with ammeters, with an internal straight tubular or cylindrical conductor for the power current, and with a hollow cylinder made of a suitable refractory insulation material surrounding the former co-axially and carrying the feeble current. Instead of choosing a circular shape, this current transformer could also be built flat.

Also in combination with other arrangements the constructional form of the modulator device as hereinbefore described could be employed analogously. In an arrangement as in Fig. 2 the device may be bent, as pointed out, in the axis *k₁ k₂* into a winding or coil and could replace the secondary winding of the current transformer *t₁*; this gives an arrangement as in Fig. 6.

My invention in its broadest aspects is hereinbefore described and hereinafter claimed in the accompanying claims, wherein, the terms "frequency changer", "frequency changer modulator", and "modulator" have all been used to define the specific form of both frequency changer and modulator but it is to be understood that the term frequency changer modulator is intended to broadly

cover the idea of either a frequency changer or a modulator or both and should, therefore, be considered in its broad sense.

Having thus described my invention, what I claim is:—

1. In combination, an iron core frequency changer modulator, a voltage step-up transformer for introducing high frequency into the modulator and a voltage step-down transformer for transferring energy output from the modulator to a load circuit.

2. In direct current saturated static frequency changing the method of reducing the saturating direct current which comprises stepping-up the high frequency voltage applied to the frequency changer to reduce the amplitude of the corresponding alternating current whereby the saturating direct current value may be brought to approximately correspond to the alternating current amplitude, and stepping-down the high frequency voltage supplied to a load circuit for the purpose of bringing the alternating current amplitude back to its normal value.

3. In direct current control modulation, the method of reducing the modulating direct current which comprises stepping-up the voltage from a high frequency source whereby the alternating current amplitude may be reduced, supplying a modulating current of a value approximately equal to the amplitude of the alternating current supplied and stepping-down the modulated high frequency voltage in the output circuit for the purpose of bringing the high frequency alternating current amplitude back to its normal value.

4. In combination, a high frequency supply circuit, a frequency changer modulator circuit, and a load circuit, voltage step-up transformer means for coupling said supply circuit to said modulator circuit, and voltage step-down transformer means for coupling said modulator to said load circuit, said voltage step-up transformer stepping up applied voltages in said modulator circuit and reducing the current in said circuit for protecting said modulator from the effects of high currents in said supply circuit.

5. In combination, a high frequency supply circuit, a frequency changer modulator, and a load circuit, said frequency changer modulator comprising an iron coated copper conductor arranged bifilar with respect to low frequency modulating and saturating currents and having parallel paths with respect to high frequency energy, means for supplying both low and high frequency energies to said frequency changer modulator, said latter named means including a transformer for coupling said bifilar frequency changer modulator to said supply circuit in voltage step-up relation whereby the amplitude of the high frequency current reaching said frequency changer is reduced, and

voltage step-down means for connecting the output of said frequency changer modulator to said load circuit.

6. In combination, an energy supply circuit, a frequency changer modulator, and a load circuit, said frequency changer modulator including a bifilar wound conductor arranged in bridge formation, transformer means for connecting said modulator with said load circuit, said means being adapted to reduce the current strength supplied to said modulator, and means for introducing the output energy from said modulator into said load circuit.
- 15 7. In combination, an energy supply circuit, a frequency changer modulator, and a load circuit, said frequency changer modulator comprising a coiled bifilar wound conductor arranged in bridge formation, voltage 20 step-up transformer means adapted to reduce current strength in the out-put circuit of said transformer for connecting said frequency changer modulator with said supply circuit, and voltage step-down transformer 25 means for introducing the output energy from said frequency changer modulator into said load circuit.

8. In combination, a high frequency energy supply circuit, a frequency changer 30 modulator, and a load circuit, said frequency changer modulator comprising a bifilar conductor arranged in bridge formation, means for supplying a modulating current to said conductor at opposite corners of said bridge 35 formation, voltage step-up transformer means for supplying high frequency energy at diagonally opposite corners of said bridge from said modulating current supply, said step-up transformer being adapted to reduce 40 the current strength supplied to said fre-

quency changer modulator from said high frequency supply circuit, and voltage step-down transformer means for delivering the output energy from said frequency changer modulator to said load circuit with a current strength substantially equal to that of said supply circuit.

9. The system claimed in claim 8 wherein said bifilar conductor is coiled and adapted for use as a portion of one of said trans- 50

10. In combination, a high frequency supply circuit, a frequency changer modulator, and a load circuit, said frequency changer modulator comprising a coiled bifilar conductor arranged in bridge formation, a source of modulating current, said modulating current being connected with said frequency changer modulator at diagonally opposite points on said bridge formation and 55 adapted to flow in a series path with respect to the said bridge, means including the said coiled bifilar conductor for inductively connecting said frequency changer modulator in voltage step-up relationship with 60 said high frequency supply, said high frequency energy transferred being adapted to flow in parallel path in said frequency changer modulator and said voltage step-up coupling being adapted to reduce the 70 amplitude of the current flowing in said frequency changer modulator to a value approximately equal to said modulating current, and means for coupling the output energy of said frequency changer modulator 75 in voltage step-down relationship with said load circuit whereby the high frequency current amplitude is transformed to approximately its original value.
